UNITED STATES PATENT OFFICE.

JOHN H. GREEN, OF SPRINGFIELD, ILLINOIS, ASSIGNOR OF ONE-HALF TO
HERBERT HARRIS, OF SAME PLACE.

BUFF-WHEEL ATTACHMENT FOR SEWING-MACHINES.

SPECIFICATION forming part of Letters Patent No. 681,783, dated September 3, 1901.

Application filed June 13, 1901. Serial No. 64,421. (No model.)

To all whom it may concern:

Be it known that I, JOHN H. GREEN, a citizen of the United States, residing at Springfield, in the county of Sangamon and State 5 of Illinois, have invented certain new and useful Improvements in Buff-Wheel Attachments for Sewing-Machines, of which the following is such a full, clear, and exact description as will enable others skilled in the art 10 to which it appertains to make and use my said invention.

My invention relates to devices of that class which are used in connection with the fly-wheels of sewing-machines or small lathes 15 or the like for operating buff-wheels or emery-wheels.

The purposes of my invention are to provide a buff-wheel attachment so constructed and arranged that it may be easily placed on 20 the fly-wheel of the machine with which it is to be used and may be conveniently detached therefrom and compactly folded, so as to occupy the smallest practical space.

The invention herein described is a modification and improvement of that set forth in 25 United States Letters Patent No. 669,633, granted to me March 12, 1901, for improvements in buff-wheel attachments.

My invention is shown in the annexed drawings, to which reference is hereby made, and in which similar reference-letters designate like parts in all of the views.

My invention is hereinafter fully described and finally recited in the claim.

Referring to the drawings, Figure 1 is a 35 perspective view of the buff-wheel attachment in connection with the fly-wheel of a sewing-machine. Fig. 2 is an enlarged longitudinal axial section on the line 2 2 of Fig.

40 1. Fig. 3 is an enlarged side elevation of the device with the arms secured alongside of each other. Fig. 4 is a vertical transverse section on the line 4 4 of Fig. 3. Fig. 5 is an enlarged side elevation of one of the arms 45 detached.

In the device described in my Patent No. 669,633 spring-arms are employed to connect the mandrel-bolt with the fly-wheel of the sewing-machine. It has been found in practice that spring-arms are objectionable be-

cause of their liability to become distorted during the operation of hardening, thereby producing inequalities in the arms which throw the mandrel-bolt out of true and cause it to wobble in turning, thereby greatly diminishing the effectiveness of the device. The arms herein described are of such form and are connected with the mandrel-bolt in such manner that all of the arms may be moved simultaneously and uniformly toward 55 or away from the axis of the mandrel-bolt, thereby assuring perfect centering and true running of the device. A tapering mandrel-bolt A is screw-threaded and has a branching head A', having forks a, in which the arms 60 B are mounted on pivots b. I preferably employ a mandrel-bolt having a head with three branches supporting three radial arms, as shown; but a head with a greater number of branches and a corresponding number of 65 arms may obviously be used. A nut D fits on the screw-bolt A, and the forward end of the bolt engages with the curved edges b' of the arms B, and as the nut is tightened the points of the arms are simultaneously and 70 uniformly drawn toward each other. On the other hand, when the nut is unscrewed the arms may be readily adjusted to fit any fly-wheel within the scope of the swing of the arms. The form of the curved front ends b' 75 of the arms B is such that the arms each have two points of contact X with the perimeter of the fly-wheel, as clearly indicated by dotted lines in Fig. 5. The bottoms of the slots a' in the branches a incline forwardly, and 80 the slots are of such depth that when the arms are folded, as shown in Fig. 3, the inner edges of the arms will rest on the bottom of the slot at the front end of the bolt-head, so that when the nut D is screwed up against 85 90 the curved ends of the arms the arms will be securely held in the position shown, the device then being in a form most convenient for transportation. The jam-nut D' serves to secure the nut D from turning. It may 95 also serve to secure an emery-wheel or a saw on the mandrel-bolt.

Having fully described my invention, what I claim as new, and desire to secure by Letters Patent, is—

In a buff-wheel attachment, a screw-threaded mandrel-bolt having an integral head with radiating slotted branches, the slots in said branches inclining forwardly and being of such depth that when the arms are folded alongside of each other the inner edges of the arms will rest on the bottoms of the slots; in combination with arms pivotally supported in the slots in said branches and having curved ends, and a nut on said mandrel-bolt

engaging with the curved ends of said arms, as set forth.

In witness whereof I have hereunto subscribed my name, at Springfield, Illinois, this 7th day of May, 1901.

JOHN H. GREEN.
